UNITED STATES PATENT OFFICE.

SETRAK ASATURIAN, OF NEW YORK, N. Y.

DESIGN FOR A SPINNING-TOP.

58,866.

Specification for Design.

Patented Sept. 6, 1921.

Application filed May 11, 1920. Serial No. 380,668. Term of patent 7 years.

To all whom it may concern:

Be it known that I, SETRAK ASATURIAN, a citizen of the United States of America, and resident of New York city, in the county and State of New York, have invented a new, original, and ornamental Design for Spinning-Tops, of which the following is a specification, reference being had to the accompanying drawings, forming part thereof.

Figure 1, is an elevation of a spinning top showing a third part of my ornamental design, and the top at rest.

Fig. 2 is an elevation of the same showing the second one-third part of my ornamental design, and the top when spinning.

Fig. 3, is an elevation of the same showing the third or complete surface of the circumference of the top and the completion of the lettering thereon.

I claim:—

The ornamental design for a spinning top, as shown.
